UNITED STATES PATENT OFFICE.

OTTO J. LIERMAN, OF NEAR REDONDO BEACH, CALIFORNIA.

SUCKER-ROD CATCH.

Application filed January 18, 1923. Serial No. 613,559.

To all whom it may concern:

Be it known that I, OTTO J. LIERMAN, a citizen of the United States, residing near Redondo Beach, in the county of Los Angeles, State of California, have invented new and useful Improvements in Sucker-Rod Catches, of which the following is a specification.

My invention relates primarily to a catch which is detachably connected to the delivery pipe of an oil well and the object thereof is to provide a catch which is easily and quickly attached to the delivery pipe that will hold the string of sucker rods in pulling a well while the top section of the string is removed from the string or while a top section is connected to the string.

In the drawings forming a part of this application Figure 1 is a side elevation of my improved catch positioned in the top of a fragment of the delivery pipe, which pipe is shown in vertical section with a portion of a sucker rod held caught thereby. Figure 2 is a side elevation of the catch detached from the pipe with the top member thrown back into inoperative position. Figure 3 is a top plan of the parts shown in Figure 2.

Referring to the drawings, 5 is a section of the delivery pipe of an oil well and 6 is a coupling member by which two sections are coupled together. My improved catch comprises a body member 7 which has a reduced lower end 8 which is externally threaded and when positioned for use screws into coupling 6. Extending centrally through the body member is a bore 9 which is large enough for the passage therethrough of coupling members of the sucker rod, one of which 10 is shown in Figure 1 coupling sections 11 of the sucker rod together. Member 10 has an internally screw threaded bore into which the ends of sections 11 screw and has flattened portions shown at 12 for the reception of a tool. The ends of sections 11 are squared at 13 also for the reception of a tool when the parts are to be joined or separated. Member 7 has ears 14 in which the handle 15 of the top member 16 is mounted by bolt 17 which passes through the ears and handle. Member 7 has a slot 18 therein which is of less width than bore 9, being preferably of a width to just permit the body of the sections of the sucker-rod to pass therethrough. Member 16 has a slot 19 therein

which is just large enough to permit the body to be turned back on the body portion of the sucker rod. Slot 19 terminates at the far edge of bore 9 when the parts are positioned for use as shown in Figure 1. Slot 18 is preferably diagonal so that in raising or lowering the sucker rod it will be kept central in bore 9.

Operation.

Assuming now that a well is to be pulled, the elevator, not shown, is attached to the top of the sucker rod in the usual well known manner and the rod is elevated so that the first sucker rod coupling is at a distance above the top of the delivery pipe. The top member of the catch is thrown back and the bottom member is then passed onto the sucker rod and is then straightened up and screwed into the top of the delivery pipe. The top member is then turned onto the rod and rests upon the bottom member. The rod is then lowered until it catches on the top member which prevents the rod from going any further. The top section can then be unscrewed and positioned in the tower. The operation is then repeated until the rod is removed.

To lower a rod a section thereof would be caught by the elevator and lowered into the pipe until the coupling caught on the catch. The elevator would then be detached and affixed to a second section which would then be positioned and screwed to the first section and both raised so as to permit the top member of the catch to be thrown back when both sections would be lowered.

After the coupling had passed through the bottom member, the top member would be thrown back to position and would catch the rod at the end and hold it and the operation would be repeated with each section until the rod was lowered. Other means can be used to detachably secure the catch upon the delivery pipe. By dividing the lower member vertically the slit therein could be omitted.

Having described my invention I claim:

1. A sucker-rod catch comprising a lower member adapted to be detachably secured upon the top of a well delivery pipe, said member having a central bore adapted for the passage therethrough of the coupling members of the sucker-rod, an upper member hingedly connected to said lower member, said upper member having a slot there-

2
in extending to the far edge of the bore of the lower member when positioned for use, said slot being vertical when positioned for use and of a less width than the diameter of 5 the coupling members of the sucker-rod.

2. A sucker-rod catch comprising a lower member having a bore extending therethrough, said member having a reduced lower end externally threaded and a slot 10 extending to the bore; an upper member hingedly connected to the lower member said upper member having a slot extending

beyond the bore of the lower member when positioned for use, the slot in the upper member being of less width than the coupling member of the sucker-rod and the bore of the lower member being of a size 15 to permit the sucker-rod couplings to pass therethrough.

In witness that I claim the foregoing I 20 have hereunto subscribed my name this 11th day of January 1923.

OTTO J. LIERMAN.
